ELECTRICAL RELAY

Marion B. Robinson, Great Neck, N. Y.

Application September 19, 1944, Serial No. 554,814

13 Claims. (Cl. 200—52)

1

This invention relates, generally, to electrical relay means, and the invention has reference, more particularly, to a novel construction of relay device which is adapted to positively and efficiently operate in response to very weak electrical currents, i. e. currents of exceedingly low amperage and voltage, for example, a current of millampere or less and of less than one-half volt; this invention being a continuation in part of my co-pending applications for United States Letters Patent, Ser. No. 418,497, filed November 10, 1941, now Patent No. 2,520,433, dated August 29, 1950, and Serial No. 447,227, filed June 16, 1942, now abandoned.

This invention has for an object to provide a novel electrical relay means which is responsive to very weak electrical currents, such as those emitted by a photo-electric cell, a crystal microphone or a carbon granule microphone or coherer, a thermopile, or from any other source of comparatively weak output of electrical energy.

The invention has for a further object to provide an electrical relay device of the character stated comprising an oscillatable needle or armature bar having a pivotal support of a kind adapted to reduce frictional resistance to needle or bar movement to a minimum, opposed or balanced tensional means for holding said needle or bar in a predetermined normal initial or neutral position, together with electro-magnetic means operative, in response to relatively weak electrical current, to move the needle or bar into circuit closing relation to a controlled circuit of relatively strong electrical current characteristics, whereby to control performance of electrical apparatus operated by the latter circuit; as e. g. to control an electrical motor, electrical ignition devices, or electrical devices of other and various kinds.

Other objects of this invention, not at this time more particularly enumerated, will be understood from the following detailed description of the same.

Illustrative embodiments of this invention are shown in the accompanying drawings, in which:

Fig. 1 is a plan view of the novel electrical relay device according to this invention, the same being illustratively and schematically shown as electrically connected through reversing switch means with an electric motor desired to be reversibly operated; Fig. 2 is a transverse vertical sectional view through the relay device of Fig. 1, taken on line 2—2 in Fig. 1; and Fig. 3 is a similar transverse vertical sectional view of a modified form of the relay device of this inven-

tion. Fig. 4 is a similar transverse vertical sectional view through the relay device of Fig. 1 taken on the line 2—2 in Fig. 1 showing the liquid when acted upon by centrifugal force, and 5 showing the position occupied in the projectile, and greatly enlarged with relation to the projectile for clarity; Fig. 5 is a similar transverse vertical sectional view through the relay device of Fig. 1 taken on the line 2—2 in Fig. 1 showing the relay device of Fig. 2 when acted upon by acceleration; Fig. 6 is a transverse sectional view of Fig. 4 taken on the line 4—4 of Fig. 4 greatly enlarged and showing the clearance for reciprocating motion of the shaft 15. Fig. 7 is a similar transverse vertical sectional view through the relay device of Fig. 1 taken on the line 2—2 in Fig. 1 showing the action of the liquid when the device is off the axis center of the projectile and is acted on by centrifugal force.

Similar characters of reference are employed in the hereinabove described views, to indicate corresponding parts.

Referring to the drawings, the relay device per se, in one illustrative form thereof as shown in Figs. 1 and 2, comprises a suitably shaped upwardly open container 10 adapted to hold a quantity of suitable liquid 11 for purposes subsequently to be stated. Mounted across the open top of said container 10 is a platform 12, preferably constructed to also serve as a cover for said container. Fitting and vertically movable within the lower portion of the container interior is a false bottom or cup 13 which may be adjusted up and down therein, whereby to predetermine the level of the liquid 11 in said container. Means is provided for adjusting said false bottom or cup 13, such e. g. as a manipulatable adjusting screw 14 which is threaded through the bottom of the container 10. Buoyantly borne by the liquid 11 within the container is a float F, which is free to revolve upon the liquid about its vertical axis with a minimum of frictional resistance to such movement. Said float may comprise a hollow body, as shown, made of any suitable material, or a solid body of low specific gravity, such e. g. as cork, wood or the like.

Affixed to the upper side or top of said float F, in upward axial extension therefrom, is an arbor 15. Said arbor passes through an opening 16 with which the platform 12 is provided, so as to project exteriorly from the container 10 and above the top surface of the platform 12. Arranged within the opening 16 is a collar 17, preferably made of felt or similar material, through 50 which the arbor loosely passes, so as to be freely

rotatable therein. Said collar 17 obstructs any accidental outward escape of the liquid content of the container 10, while at the same time operating to prevent lateral displacement of the arbor and the float to which the latter is connected.

Secured to the exterior upper end portion of said arbor 15 is a metallic needle or bar 18. Said needle or bar 18 comprises at least one laterally extending arm, and, as shown, when a double effect relay is desired, comprises oppositely extending arms 19 and 20. Said needle or bar 18 is normally held in a predetermined initial or neutral position by balanced tensional means of small force, which, although sufficient to retain the needle or bar in a desired neutral position will nevertheless offer but little and easily overcome impedance to operative movement of the needle or bar. One illustrative form of such balanced tensional means comprises a pair of coiled hair-springs 21 and 22, the same being respectively anchored by their inner ends to anchor posts 23 and 24 respectively affixed to the platform 12 on opposite sides of arbor 15; the outer ends of said hair-springs being secured, in any suitable manner, to diametrically opposite sides of said arbor 15, or, if desired, directly to the central part of the needle or bar 18 itself. One said hair-spring is coiled clockwise and the other anti-clockwise, so that their tensional stresses as transmitted to the needle or bar are normally in balanced opposition, with the result that rotative swing of the needle or bar 18 in one direction, e. g. clockwise direction, increases the tension of one said spring and relaxes that of the opposite spring, while rotative swing of the needle or bar 18 in the opposite direction, e. g. anti-clockwise direction, increases the tension of said opposite spring and relaxes that of said first mentioned spring. When, however, the needle or bar is released from the effect of a rotation inducing force, the stressed spring will return said needle or bar to its predetermined normal initial or neutral position.

Mounted on the platform 12 is electro-magnetic means for applying rotation inducing force to the needle or bar 18, the same being disposed in lateral opposition to a free end portion of the arm or arms of the needle or bar. In the double effect form of relay shown, an electro-magnet 25 is so opposed to the arm 19 of the needle or bar and a similar electro-magnet 26 is so opposed to the arm 20 of said needle or bar. Each electro-magnet is connected in circuit with a desired independent source of comparatively weak electrical energy to which the relay device is desired to be responsive. For example, as illustratively shown in Fig. 1, the electro-magnet 25 is connected by circuit wiring 27 to a photo-electric cell 28 from which, when energized, magnetizing current is supplied to said electro-magnet 25. In like manner, the electro-magnet 26 is connected by circuit wiring 29 to a photo-electric cell 30 from which, when energized, magnetizing current is supplied to said electro-magnet 26.

When operated by attractive force of an activated electro-magnet, the needle or bar 18 will be caused to swing toward said magnet, and by such movement become operative, through suitable circuit closing means, to close a circuit of relatively strong electrical current character which it is desired to control by the functioning of the relay device.

By way of illustration, but not by way of limitation, the above-described novel relay device

of this invention is shown in double effect form, and as arranged to control the circuits of reversing switch means to in turn control delivery of operating electrical current to an electric motor desired to be reversibly operated. Such arrangement, as shown in Fig. 1, comprises a battery 31, or other suitable source of relatively strong energy output, from which extends an output conductor 32, which, if desired, may include in the line thereof a manually operable switch 33. Leading from said conductor 32 is a conductor 34 which is connected to a stationary contact terminal 35 disposed in the path of operative movement of the arm 19 of the needle or bar 18. Adjacent to said contact terminal 35 is another stationary contact terminal 36 which also lies in the path of movement of said needle or bar arm 19. Said needle or bar arm 19 carries a contact member 37 which, by operative movement of said arm 19, may be carried into bridging circuit closing engagement with said stationary contact terminals 35 and 36. A conductor 38 leads from said contact terminal 36 to one pole of one coil 39 of a solenoid, the opposite pole of which is connected to a return conductor 40 leading back to the battery 31. Said solenoid coil 39, when energized, is operative to move the solenoid armature 41 in one direction, e. g. from right to left as shown. Leading from the battery output conductor 32 is a conductor 42 which is connected to a stationary contact terminal 43 disposed in the path of operative movement of the arm 20 of the needle or bar 18. Adjacent to said contact terminal 43 is another stationary contact terminal 44 which also lies in the path of movement of said needle or bar arm 20. Said needle or bar arm 20 carries a contact member 45 which, by operative movement of said arm 20, may be carried into bridging circuit closing engagement with said stationary contact terminals 43 and 44. A conductor 46 leads from said contact terminal 44 to one pole of another coil 47 of the aforesaid solenoid, the opposite pole of which is connected to the battery return conductor 40. Said solenoid coil 47, when energized, is operative to move the solenoid armature 41 in an opposite direction, e. g. from left to right. At its left hand end, the solenoid armature 41 bears an insulator plate 48 which carries separate contact points 49 and 50 which oppose and are adapted to be respectively moved by solenoid operation into engagement with separate stationary contact points 51 and 52. Through these contact points 45-50 and 51-52 the field coils 53 and windings of armature 54 of an electric motor are connected in series with the battery 31, by a circuit completed through conductor 55 to one side of the field coils 53, leaving the opposite side of the latter through conductor 56 to conductor 57, thence through closed terminal contacts 51-49 to the conductor 58 which connects with one side of the windings of the motor armature 54, thence from the opposite side of the latter through conductors 59-60 and closed terminal contacts 50-52, back through conductor 61 to battery return conductor 40 of the battery 31. In like manner, at its right hand end, the solenoid armature 41 bears an insulator plate 62 which carries separate contact points 63 and 64 which oppose and are adapted to be respectively moved by solenoid operation into engagement with separate stationary contact points 65 and 66. Through these contact points 63-64 and 65-66 the field coils 53 and windings of armature 54 of the electric motor are connected in series, for flow of operating current in

opposite direction through the armature windings by a circuit completed through conductor 55 and field coils 53 to conductor 56-57, thence through closed terminal contacts 66-64 to the conductor 68-59 which connects with the opposite sides of the windings of the motor armature 54, thence from said windings through conductors 58-69 and closed terminal contacts 63-65, back through conductor 70 to battery return conductor 40.

In the operation of the relay device to control the reversible electric motor, described in the above example of relay use, in the event that the photo-electric cell 28 is excited or becomes active, the current generated thereby will flow through the electro-magnet 25, thereby attracting the arm 19 of the needle or bar 18, so that the latter will swing upon the substantially frictionless pivotal support provided by the float F, thus moving the arm 19 to carry its contact member 37 into circuit closing engagement with the contact terminals 35-36, whereupon current from the battery 31 excites solenoid coil 39 whereby to move the solenoid armature 41 in direction to close the switch contacts 49-51 and 50-52 to complete the circuit which supplies battery current to the electric motor to effect operation thereof in one direction. When the photo-electric cell 28 becomes inactive, and the electro-magnet 25 is thereupon demagnetized, the stressed hair-spring 21 will return the needle or bar 18 to normal initial or neutral position, thus interrupting the aforesaid motor actuating circuit. On the other hand, in the event that the photo-electric cell 30 is excited or becomes active, its current output will energize the electro-magnet 26, thereby attracting the arm 20 of the needle or bar 18, so as to cause said arm to carry its contact member 45 into circuit closing engagement with the contact terminals 43-44, whereupon current from the battery 31 excites solenoid coil 47 whereby to move solenoid armature 41 in direction to close the switch contacts 66-64 and 63-65 to complete the circuit which supplies battery current to the electric motor to effect operation thereof in the opposite direction. In like manner, when said photo-electric cell 30 becomes inactive, and the electro-magnet 26 is thereupon demagnetized, the stressed hair-spring 22 will return the needle or bar 18 to normal initial or neutral position, thus interrupting the last mentioned motor actuating circuit.

The height of liquid 11 within the container 10 may be selectively predetermined whereby to raise or lower the position of the float F to so dispose the float and the needle or bar 18 supported thereby that the latter is properly disposed in alignment with the electro-magnets 25 and 26. This may be done by raising or lowering the false bottom or cup 13 by manipulation of the adjusting screw 14.

In Fig. 2 the distance between the outer sides of the float F and the inner sides of the container 10 is smaller than the distance between the bottom of the float F and the false bottom 13. Therefore, normally, a comparatively greater quantity of liquid is found at the bottom of the float than at the sides of it, which liquid at the sides extends beyond the vertical center of the float F. This has no significance as far as the cushioning action is concerned and shows only the amount of liquid which will be displaced along the sides of the float F and the sides of the container 10 to properly cushion the float.

Because of this construction, with the relay device contemplated by me, as the projectile is

accelerated, the liquid 11 is not permitted to pass up the sides of the float F at any fast rate of speed because of the small space between the outer sides of the float F and the inner sides of the false bottom 13. Thus a cushioning effect is provided at the bottom of the float F because of the smallness of annular space between the outer sides of the float and the inner sides of the false bottom which provides friction to slow down passage of liquid 11. Therefore means is provided for cushioning the needle 19-20 or other delicate instruments placed on the arbor 15 against setback or inertia.

It is foreseen that if in an embodiment of my invention of the relay device where a protection against damage of delicate instruments and having a float of such size that more liquid 11 is at the sides of the float or that the liquid has more density or viscosity and the float and the instruments sustained by the float are of light weight, then the movement of the float F might be in the direction of the projection rather than the reverse, or the float might remain stationary and be cushioned thereby.

As Archimedes' principle proves that a body placed in a liquid is buoyed up by a force equal to the weight of the displaced liquid therefore as shown in Fig. 2 very little liquid has been displaced. When the float and instruments sustained by the float is of greater weight then more liquid would be displaced unless the liquid were denser. The inertia pressure of the float on the liquid forces the liquid to be displaced along the sides and on to the top of the float. The displacement of the liquid and the cushioning of the float would depend on the space between the outer sides of the float and the inner sides of the false bottom and the viscosity or density of the liquid.

In the invention, the distance between the outer sides of the float F and the inner sides of the false bottom 13 would be determined by the density or viscosity of the fluid and the weight of the float to insure the proper cushioning.

As the float F must travel opposite the direction of motion due to inertia and the liquid 11 can find an escape from an increased pressure of the float by traveling with the direction of motion or in the space between the float and the container the float would therefore travel opposite the direction of motion and the liquid with the direction of motion. This insures that, upon set-back, liquid is forced in the space between the inner sides of the container and the outer sides of the float so that the float and instruments sustained by the float are fully cushioned against the inertia pressure of the float F, as the projectile is accelerated.

For some practical uses it may be desirable as shown in Fig. 5 to so arrange the space between the outer sides of the float F and the inner sides of the false bottom 13 with more space so that upon acceleration of the projectile the float F and the means such as needles 19 and 20 and the hair springs 21 and 22 or other delicate instruments will be cushioned as they move opposite the direction of motion until the bottom of the float F will rest or abut against the inner top surface of the false bottom and the needles 19 and 20 and the hair springs 21 and 22 or other delicate instruments will rest or abut the top surface of platform 12. This however is not necessary where used to sustain other delicate instruments as the space between the outer sides of the float F and the inner sides of the false bottom 13 may be less to provide more friction

so that the liquid 11 will pass through the opening slower and the bottom of the float will not reach the top surface of the false bottom 13 during acceleration but the cushioning will take place because of the movement of the liquid through the opening in the direction of motion and thereby a cushioning effect will occur during acceleration.

It will of course be understood where the liquid sustains or buoys the float at different levels as seen in the several views then the electro-magnets 25 and 26 and the contacts 35-36 and 43-44 must be raised or lowered so that when the needles 19 and 20 are attracted to either of the electro-magnets 25 and 26 either of the contacts 37 or 45 will contact either the contacts 35-36 or 43-44 to complete the circuit. When the float is withdrawn as shown in Fig. 5 or as will be understood in the other views any movement of the needles could not complete a circuit when in its withdrawn position.

It is foreseen that the device contemplated by me may be rearranged in a different manner without departing from the scope of my invention so that the float F may be forced in the direction of projection rather than the reverse, or the float might remain stationary depending on the density of liquid and the weight of the float and parts sustained by the float.

It is also foreseen in the invention contemplated by me where my invention is used in a rotating body as shown in Fig. 4 and placed on the axis of a rotating body the space on the sides between the float F and the container 10 and the space between the top of the float F and the platform 12 will not accommodate all of the liquid when the liquid is acted on by centrifugal force thereby leaving enough liquid 11 in the space between the bottom of the float and the false bottom as shown to buoy the float to an operative position. The action of the liquid when used in a rotating body would be to force the float upward until the liquid passed through the small opening between the outer sides of the float and the inner sides of the false bottom until the liquid occupies the position shown in Fig. 4. If as shown in Figs. 2 and 4 these devices are used in a projectile where the float and liquid are first acted upon by acceleration and secondly by centrifugal force then the liquid would first be acted upon by acceleration to force the liquid from the position as shown in Fig. 2 through the opening between the outer sides of the float and the inner sides of the false bottom and act as previously described. After acceleration has ceased the liquid is acted upon by centrifugal force causing the liquid to take the position as shown in Fig. 4 and because the space between the outer sides of the float and the inner sides of the container and the space between the top surface of the float and the bottom surface of the platform 12 will not accommodate all of the liquid there will still be sufficient liquid at the bottom to buoy the float. If less space is desired in container 10 the manipulating screw 14 may be readjusted to lift or raise the false bottom 13 so that less space is provided in the container 10 between the top of the float and the platform and the bottom of the float and the false bottom for the liquid to occupy or move in. The float will remain as shown in Fig. 4 during centrifugal force caused by rotation and enough liquid will remain at the bottom of the float to buoy the float at the desired height.

It is not necessary that the liquid container be placed on the axis center of a rotating body

but as shown in Fig. 7 may be placed off the axis center and when the liquid is acted on by centrifugal force the liquid will be pulled to one side of the float in the space between the float and the container and the space between the top of the float and the platform and the space between the bottom of the float and the false bottom, but as these spaces will not accommodate all of the liquid therefore there will be enough liquid in the space between the bottom of the float and the false bottom to buoy the float and keep it in an operative position. The action of the liquid when used in a rotating body would be to force the float upward until the liquid passes through the small opening between the outer left side of the float and the inner left side of the false bottom as viewed in Fig. 7 until the liquid occupies the position as shown in Fig. 7. However if as shown in Figs. 2 and 7 if these devices were used in a projectile where the float and liquid are first acted upon by acceleration and secondly by centrifugal force then the liquid 11 will be in the position as viewed in Fig. 7 because the space between the outer left hand side of the float and the inner left hand side of the container and the space between the top of the float and the platform will not accommodate all the liquid. If less space is desired in container 10 the manipulating screw 14 may be readjusted to lift or raise the false bottom 13 so that less space is provided in the container 10 between top of the float and the platform and the bottom of the float and the false bottom the liquid thereby has less space to move or occupy. The float will remain as shown in Fig. 7 during centrifugal force caused by rotation and enough liquid remains at the bottom of the float to buoy the float to an operative position.

Fig. 6 is a greatly enlarged view of the shaft 15 and the washers or collar 17 showing the clearance for reciprocating motion between the washers or collar 17 and the shaft 15. It will of course be understood that the clearance between the shaft and collar as shown must be exaggerated in order to illustrate this clearance but in practice this clearance would be 0.0002 of an inch or less which of course can not be illustrated. This clearance should be small enough so that the collar 17 will prevent the shaft and float from lateral displacement and the shaft 15 can freely rotate therein.

Referring now to Fig. 3 of the drawings, there is shown thereby a somewhat modified form of the relay device according to this invention, wherein a different type of substantially frictionless pivotal support for the needle or bar 18 is provided. In this modified arrangement, a supporting platform 71 is provided and supported above and in spaced opposition thereto is a cross-head 72. Suitably mounted on said platform 71 is a lower jeweled bearing 73, and suitably mounted on the cross-head 72 is an upper jeweled bearing 74 arranged in opposed and aligned relation to said lower jeweled bearing. The arbor 15 of the needle or bar 18 is provided at its opposite ends with needle point bearing terminals 75 which respectively engage the respective jeweled bearings 73 and 74, whereby to provide a substantially frictionless pivotal support for said needle or bar 18. In this modified arrangement, a somewhat different form of balanced tensional means is provided for yieldably holding the needle or bar 18 in normal

initial or neutral position. This modified balanced tensional means comprises an upper spirally coiled hair-spring 16, having one end fixed to the upper part of the arbor 15 to wind around the same, and with its opposite end anchored to an anchor post 11 suitably affixed to the cross-head 72, and a lower spirally coiled hair-spring 18, having one end fixed to the lower part of the arbor 15 to wind around the same, and with its opposite end anchored to an anchor post 19 suitably affixed to the platform 11.

As shown in the accompanying drawings, the needle or bar 18 is so related to associated controlled circuit contact devices, as to open a controlled circuit when the needle or bar is disposed in normal initial position, and to close said controlled circuit when the needle or bar is moved by the electro-magnetic means; it will nevertheless be understood by those skilled in the relay art, that the reverse of such arrangement could be provided for and utilized so that a controlled circuit would be closed when the needle or bar is disposed in normal initial position and would be opened when the latter is moved by the electro-magnetic means.

The needle or bar 18 may itself be magnetised, as e. g. is a compass needle, that is, may itself constitute a magnet, the pull of its magnetism alone, when the electro-magnets 25 and 26 are demagnetised, being insufficient to overcome the balancing action of the springs 21—22 or 76—78, but which when the electro-magnets 25 or 26 are magnetized, is accumulative therewith, in aid of operative movement of the needle or bar against the spring tension. Such conditions increase the sensitivity of the relay in response to the pull of the magnets 25 or 26 when the latter are but weakly magnetized by weak electrical current.

It will be obvious that the arbor 15 of needle 19—20 is capable of axial movement relative to the container top, whereby the construction is adapted for use in a shell or projectile so that under inertia or force of set back, occurring when the shell or projectile leaves the gun, the needle structure may be stopped against the container top, and the float F would be protected from shock until the force of acceleration diminishes, at which time the float F would be buoyed up by the liquid in the container 10, and the needle structure would be returned to normal operative position. In this connection, the springs 21—22 could, if desired, be placed above the needle 19—20, so that the underside of the latter may directly abut the top surface of the container under the inertia reaction referred to.

It will be understood that changes may be made in the relay structure shown in the drawings and above described without departing from the scope of this invention as defined by the following claims. It is therefore intended that all matter contained in the above description or shown in the accompanying drawings shall be interpreted as illustrative and not in a limiting sense.

I claim:

1. In electrical relay device comprising a container having a body of liquid therein, a float supported by said liquid, an axial arbor upstanding from said float, a bar affixed to said arbor, said float being adapted to rotate in the liquid and said arbor rotatable with said float to permit oscillation of said bar with said arbor as an axis, said float being substantially free from frictional resistance to its turning movements, the buoyancy of said float being effective to cushion

ion said bar against set-back when subject to displacement, balanced tensional means for yieldably holding said bar in a normal initial position, a plurality of electro-magnetic devices for attracting opposite end portions of said bar and a pair of normally open switches and means on each end portion of said bar for closing one of said switches upon energizing one of said electro-magnetic devices.

2. A relay device for use in an electrical circuit of a projectile, comprising contact means incorporated in said circuit, a needle arranged for rotating action so as to close said circuit through co-action with said contact means when influenced by an external magnetic force, said needle mounted in the device whereby the needle is set-back upon acceleration of the projectile, and bearing means for cushioning said needle against set-back during acceleration of said projectile, said bearing means comprising a buoyant yieldable element in which said needle is mounted, said yieldable element responding to said force of set-back so as to permit the withdrawal of said needle from co-action with said contact means whereby said needle is inoperative to close said circuit during said acceleration, said yieldable element further serving as a bearing member for permitting said rotating action so as to permit closing of said circuit through the influence of said magnetic force when the acceleration of said projectile has ceased.

3. A relay device for use in an electrical circuit of a projectile, comprising contact means incorporated in said circuit, a needle arranged for rotating action so as to close said circuit through co-action with said contact means when influenced by an external magnetic force, said needle mounted in the device whereby the needle is set-back upon acceleration of the projectile, a shaft on said needle and bearing means for cushioning said needle against set-back during acceleration of said projectile, said bearing means comprising a chamber, a supply of fluid in said chamber, said fluid being operative to buoy and support said shaft and needle in position to coact with said contact means when said needle is buoyed to an outward position relative to said chamber, said fluid being further operative to cushion set-back of said needle during acceleration of said projectile by permitting the withdrawal thereof to an inward position in said fluid against the elevating force of said buoyancy, said inward position being such as to render said needle incapable of co-acting with said contact means whereby said electrical circuit cannot be closed during acceleration of said projectile, said buoyancy restoring said needle to an operative position when acceleration has decreased, said needle shaft being rotatable in said fluid so as to permit said rotating action of said needle.

4. In an electrical relay device, a liquid container having a buoyancy liquid therein, a cover for the container, a float in the container supported by the liquid therein, a shaft having the lower end thereof on the float at the center thereof and extending up therefrom through the cover in alignment with the vertical axis of the float for oscillation about said vertical axis, said shaft reciprocable in the said cover, a plurality of electromagnetic means and a bar mounted on the shaft above the cover and adapted to be attracted to one or the other of said electro-magnetic means, said bar being of magnetic material and having opposite poles at each end and mounted adjacent to the electromagnetic means,

the buoyancy of the liquid supporting the float and cushioning said float upon displacement of the float along its vertical axis.

5. An electrical device according to claim 4, the distance from the bar to the bottom of the float being equal to the distance of the cover to the bottom of the container.

6. A relay device mounted in a projectile and for connection in an electrical circuit arranged in the projectile, said device including a pair of contacts for arrangement in said circuit, a bar mounted on the device for movement to bridge said contacts upon influence by an external magnetic force and bearing means for cushioning said bar against set-back and incapacitating said bridging action imposed by the acceleration of said projectile, said bearing means comprising a yieldable element for absorbing said set-back, said yieldable element permitting movement of said bar for said bridging action when said acceleration of the projectile has ceased.

7. A relay device for use in an electrical circuit of a projectile, comprising contact means incorporated in said circuit, a needle arranged for movement upon being influenced by an external magnetic force so as to close said circuit through co-action with said contact means, a shaft carrying said needle, and bearing means for said shaft whereby said needle may move to a position of co-action with said contact means, said bearing means comprising a chamber, a supply of fluid in said chamber, means normally maintaining said needle and said shaft in an outward position by the buoyancy of said fluid for said co-action of the needle with the contact means, said means for normally maintaining the needle in outward position movable in said fluid to permit said co-action, said last mentioned means during acceleration of said projectile serving to maintain said shaft and needle in an inward position against the elevating force of buoyancy of said fluid whereby said needle is inoperative to close said circuit during said acceleration.

8. In combination with a projectile, a first member, a second member fastened to the projectile, said first member being movable with respect to the second member in the interior thereof from normal position relative thereto upon acceleration of the projectile, the interior of said second member comprising a means for holding therein a fluid positioned between the first and second members and a buoyant fluid in the said fluid holding means, said buoyant fluid being displaceable from between said first and said second members for absorbing shock to the first member incurred by relative movement from normal position, and means controlling rate of displacement of said fluid including small opening means between the first and second members.

9. In combination with a projectile, a first member, a second member fastened to the projectile, one of said members being movable from a normal position relative to the other member in one direction due to its inertia upon accelerating the projectile, one of said members being arranged to hold in the interior thereof a means between the members for retarding movement of the first mentioned member away from normal position in said one direction, said means for automatically returning said first mentioned member to normal position when the acceleration ceases.

10. In combination, a projectile; an actuating device within the projectile, the actuating device including a container rigid with the projectile

for holding a quantity of fluid; a float member disposed in the fluid and having limited vertical movement relative to the container; the container being shaped so that when the float member is caused to move downwardly relative to the container upon the upward acceleration of the projectile, the fluid is caused to flow from one portion of the container to another portion thereof due to the force exerted by the float member; means restricting the flow of said fluid so as to retard the downward movement of the float member; and actuating means connected to the float member.

11. In combination, a projectile; an actuating device within the projectile, the actuating device including a container rigid with the projectile for holding a quantity of fluid; a float member disposed in the fluid and having limited vertical movement relative to the container; the container being elongated and extending upwardly so that when the float member is caused to move downwardly relative to the container upon the upward acceleration of the projectile, the fluid is caused to flow in the direction opposite to the movement of the float member; means restricting the flow of said fluid so as to retard the movement of the float member; and actuating means connected to the float member.

12. In combination: a closed liquid container; a predetermined amount of liquid in the container, a float within the container disposed on the liquid for angular movement about the axis of the float, an axial arbor extending from the float; means affixed to the arbor to provide an arm transversely to the arbor; a member fixed with respect to the container in a position to be engaged by the arm upon angular displacement of the float relatively to the container when the float has a predetermined axial position with respect to the container; the float being axially movable relatively to the container upon application of forces to the container accelerating it in the direction of the float axis, and the float and container having relative sizes to provide for such an amount of axial movement that the arm may be axially displaced from the fixed member to prevent engagement of the same despite angular displacement of the float relatively to the container.

13. The combination of claim 12, wherein the container has a movable wall movable into and out of the container to vary the size thereof; and means selectively to position said movable wall and thereby to determine the normal floating elevation of the float relatively to the container.

MARION B. ROBINSON.
